GIN BREAST ADJUSTER

William A. Jones, Ada, Okla.

Application February 11, 1939, Serial No. 255,998

1 Claim. (Cl. 19—55)

This invention relates to an adjuster for gin breasts.

Means heretofore employed for raising and lowering the breasts of gins have generally been objectionable because they allow the breasts to fall and become injured. Furthermore they do not allow for the various adjustments of the breasts which are desirable to meet different conditions.

10 An object of the present invention is to provide an adjuster which can be applied to different kinds of gins and, when properly positioned, can be readily actuated to move the breast to any one of several positions so as to adapt it 15 properly to the conditions present.

A further object is to provide a means whereby the breast can be swung well out from the gin to permit the operator to clean out lint, cotton and seed from the ribs without danger of injury 20 to the hands.

A still further object is to provide an adjuster which will hold the breast securely in any position and prevent it from falling and becoming injured.

25 Another object is to provide an adjuster which enables the operator quickly to bring the gin breast into position to avoid injury or fire hazard resulting from backlash occurring when the condenser stops or when air or the brush fails to 30 take cotton from the saws.

With the foregoing and other objects in view which will appear as the description proceeds, the invention consists of certain novel details of construction and combinations of parts hereinafter more fully described and pointed out in the claim, it being understood that changes may be made in the construction and arrangement of parts without departing from the spirit of the invention as claimed.

40 In the accompanying drawings the preferred form of the invention has been shown.

In said drawings

Figure 1 is a perspective view of a portion of a gin and showing one side portion of the adjuster connected thereto.

45 Figure 2 is a side elevation of the adjuster.

Figure 3 is a plan view thereof.

Referring to the figures by characters of reference A designates a portion of a gin provided 50 with the usual breast B mounted to swing at its lower end relative to the brush C.

The present invention includes a rock shaft 1 mounted in suitable bearings 2 carried by the bottom portion of the gin and fixedly connected 55 to one end of this shaft is an operating lever 3

provided with a spring-pressed dog 4 which can be shifted by means of a grip 5. The dog is adapted to engage any one of a series of teeth 6 carried by a segment 7 which is fixedly mounted at one side of the gin in a plane parallel with 5 the path of movement of lever 3.

Secured to shaft 1 adjacent to each end thereof is a shifting arm 8 located outside of the gin and pivotally attached, at its upper end, as by means of a transverse pin 9, to a thrust rod 10 10 and a guide rod 11. These rods are extended substantially in opposite directions, rod 11 being 15 slidable in a stationary bracket 12 and carrying a coiled spring 13 which bears at one end against the bracket and at its other end 15 against a collar 14 or the like mounted on rod 11 adjacent to the shifting arm 8.

Each of the thrust rods 10 is attached to a cross rod 15 which, as shown, is mounted in brackets 16 secured to and depending from the bottom of the breast B. The opposite ends of each thrust rod 10 are preferably oppositely screw-threaded, one end being in engagement with a sleeve 17 engaged by pin 9 while the other end engages a yoke 18 engaging rod 15. 25 Thus each rod 10, when rotated in one direction, can shift the yoke 18 away from sleeve 17 and, when rotated in the opposite direction will draw them toward each other. Thus a minute adjustment can be effected for the purpose of 30 properly positioning the shifting arms 8 relative to the cross rod 15.

Normally the breast B of the gin is closed against the bottom of the gin, this being the proper position while dry cotton is being ginned. 35

The spring 13 will be compressed under these conditions and dog 4 in engagement with one of the teeth 6 at the back end of segment 7.

The spring is of sufficient strength to shift the breast forwardly when the dog is disengaged from the teeth 6 but it is not strong enough to 40 push the dog out of engagement with the teeth.

Should a supply of damp cotton be fed to the gin, the operator, by a light upward pressure on the grip 5, can withdraw dog 4 from engagement with segment 7 and the breast will thus be 45 quickly shifted forwardly as far as desired. This release is also desirable when ginning tough cotton or long staple cotton. Should there be a backlash in the gin due to failure of the condenser or due to accumulation of cotton on the saws, the gin breast can readily be released to 50 swing outwardly as far as necessary to avoid any fire hazard or the breaking of ribs. By grasping the lever the operator can quickly move the 55

breast to any position and at no time is there any danger of the breast slamming shut and becoming broken.

It will be apparent that the structure herein described can be attached readily to different types of gins and constitutes an efficient means whereby the breast of the gin can be opened and closed as necessary.

It will be noted that the teeth 6 are in the form of ratchet teeth so that when lever 3 is moved forwardly the dog will slip over the teeth but when the lever is thrust backwardly it cannot move unless the dog is first disengaged from the teeth. This insures against slamming of the breast and this slamming is further avoided by the cushioning action of the spring.

What is claimed is:

The combination with a gin having a breast mounted for swinging movement, of a rock shaft, an arm movable therewith, a stationary guide bracket, a guide rod pivotally connected to the arm and slideable in the bracket, a spring mounted on the guide rod and engaging the bracket,

said spring being normally under compression, a thrust rod, adjustable pivotal connections between the thrust rod and the arm and gin respectively, an operating lever extending from and movable with said rock shaft, an arcuate series of closely arranged ratchet teeth fixedly mounted adjacent to and parallel with the path of movement of the lever, said teeth being pitched in the direction of thrust of the spring, a dog carried by the lever for engagement with the teeth, and a spring carried by the lever and dog for urging said dog into engagement with any one of the teeth, said spring of the dog being of sufficient strength to hold the dog normally in engagement with one of the teeth and against the thrusting action of the spring on the guide rod, said lever being movable in one direction to swing the breast to open position against the resisting force exerted by the spring of the dog, and said teeth and dog cooperating normally to hold the lever and breast against movement in the opposite direction.

WILLIAM A. JONES.
